MARCEL WAVER

Karl Leuser, New York, N. Y.

Application August 20, 1930. Serial No. 476,668

3 Claims. (Cl. 132—32)

This invention relates to electrically heated hair waving devices and more particularly to a hair waving device of the kind designed to produce waves of the "Marcel" type.

5 There are two general methods of waving the hair, viz., those methods wherein heat is applied to produce the wave and those methods wherein heat is not used. In the latter group are to be found the so-called "finger wave" and the "water wave" methods. These non-heat processes can be used only on hair which is naturally or permanently curly, since the effort is directed towards re-setting a natural or permanent wave or curl rather than to produce an 10 artificial wave. In the former class, i. e., the heat processes, there are to be found the so-called "permanent" waving and the "marcel" waving, as well as the ordinary curl produced by the usual curling iron.

20 The permanent and marcel waves are, of course, designed for naturally straight hair since the application of heat in some manner is necessary to produce a wave of any degree of durability in this type of hair. Permanent waves 25 are objectionable for the reason that the excessive heat applied therein is always injurious to the hair. Likewise, the usual method of giving the marcel wave is objectionable in that the externally heated iron which is employed is injurious to the hair and the expense of having it done by professional wavers is quite considerable.

30 The object of the present invention is to provide a hair waving device which is simple in construction and inexpensive to manufacture and which, by virtue of its novel construction, particularly of the heat unit, will remove all danger of burning the hair.

40 Another object of the invention is to provide a device of this kind which may be used in the home by the person desiring the wave and will produce a wave of equal beauty and attractiveness to that of the professional waver. Thus the cost of having an attractive wave is reduced 45 to an absolute minimum in that a girl may spend a short time every few days and have the hair always attractively waved.

50 The invention also contemplates a hair waving device which will wave the hair in two planes simultaneously, thereby giving it an irregular corkscrew effect which will impart an attractive and artistic wave to the hair appealing to the aesthetic sense.

55 Other objects and advantages of the invention will be hereinafter specifically pointed out,

or will become apparent, as the specification proceeds.

With the above indicated objects in view, the invention resides in certain novel constructions and combinations and arrangement of parts, clearly described in the following specification and fully illustrated in the accompanying drawings, which latter show embodiments of the invention as at present preferred.

In said drawings:

Fig. 1 is a side elevation of the embodiment, partially in section.

Fig. 2 is a plan view partially in section, of the back of the heating structure.

Fig. 3 is a plan view of the front of said heating structure.

Fig. 4 is a section on line 4—4 of Fig. 2.

Fig. 5 is a section on line 5—5 of Fig. 2.

Fig. 6 is a side elevation of the main body of the heating structure.

Fig. 7 is a back plan view of same.

Fig. 8 is a section on lines 8—8 of Fig. 7.

Fig. 9 is a plan view of the front cover for the heating structure.

Fig. 10 is a side elevation of same.

Fig. 11 is a section on line 11—11 of Fig. 9.

Fig. 12 is a rear plan view of the sliding comb mounted on the heating structure.

Fig. 13 is a side elevation of same.

Fig. 14 is a section on line 14—14 of Fig. 13.

Fig. 15 is a view of the hub of the device.

Similar reference characters refer to similar parts throughout said drawings.

Referring now more particularly to said drawings, the device includes a frame 10, which carries the heating unit, hereinafter described, and is integral with a handle structure 11. This frame is made of suitable sheet metal and includes a curved back portion 12 and side portions 13. These side portions are at right angles to the back portion, as indicated in Fig. 8, and are provided with a series of prongs or teeth 14 along the edges thereof. The frame is also provided with an end portion 15, which is bent at right angles to the upper end of the back portion. A cover plate 16 is also provided for the frame 10. This plate is also constructed of sheet metal and includes a curved front portion 17 and side portions 18 and an end portion 19. The general shape to which this plate is bent is shown in Fig. 12, the plate being secured to the frame as follows: The lower portion 20 of the frame is bent in a circle to form a collar, having a flattened portion 21 on the top thereof. A 110 tongue portion 22 at the lower end of the plate

16 is inserted under this flattened portion 21, and the opposite end portion 19 of the plate is secured to the end portion 15 of the frame by means of a screw 23 held in internally threaded apertures 19' and 15', respectively, in said end portions. This plate 16 serves both as a cover for a heating unit, hereinafter described, and also as a carriage for a sliding comb structure 25. This comb structure includes a base 26 constructed of sheet metal, and a plurality of metal teeth 27 secured thereto. These teeth are semi-circular in shape as shown in Figs. 4 and 15. The base of the comb structure is provided with an extension portion 28 which is slidably received in a slot 29 in the end portion 15 of the frame structure. The base structure 25 is also provided with ears 29 which are engaged by flanges 30 in the cover plate 16. A cutaway portion 31 in the lower end of said cover plate receives the two lower ears 29' in the base. The lower end 29' of the base passes under the portion 32 of said cover plate and through a slot 32'. Thus it will be seen that the comb is slidably mounted on said cover plate and may move longitudinally of the frame. The base is also provided with a U-shaped bracket 33 having a rectangular opening 33' therein. The comb is actuated by means of a lever 34 pivotally mounted to a bracket 36 on the back 12 and being integral therewith. Integral with this lever 34 is an extension portion 37 which carries a pin 37'. Thus, when the lever is pulled downwards, the comb is caused to move upwards, and vice versa.

35 The heat unit is placed underneath this cover plate 16. This heat unit includes a heating element 39 constructed of suitable resistance wire and is insulated on one side by a relatively thick piece of asbestos or other suitable material 40 and on the opposite side by a somewhat thinner piece of asbestos 41. It will be readily appreciated from Fig. 4 that the position of the heating unit is such as to heat the entire cover plate 16. The handle structure 11 is hollow and an electric insulated wire 42 passes through this handle, through the pivot 43 and into the heating unit, the pivot portion being hollow as indicated at 11' in Fig. 3. A second handle 44 carries two fork members 45 at the opposite end thereof. These fork members are curved in order to fit into frame and are provided with a concave side shown in Figs. 4 and 5, in order to engage the convex sides of the face plate 16 thereby providing a larger ironing or pressing surface.

60 To use the apparatus the electric current is turned on until the desired heat is obtained. The forked members 45, are then inserted into the hair close to the scalp and the handles are then drawn closed, thereby applying the heat unit to the hair. The position of the front plate 16 in relation to the forked members is best shown in Fig. 4. It will then be seen that the shape of the plate member when the hair is pressed tightly to same will produce a curl on one plane. The actuating lever 34 is then drawn by the operator, causing the sliding comb structure to move, thereby giving the hair a second curl on another plane, producing a generally spiral effect. As soon as the curl is well formed, the device is withdrawn and inserted in an adjacent portion of the hair and the operation repeated, the comb structure, however, being moved in the opposite direction in this second wave.

It is obvious that when the comb structure is moved, thereby drawing the hair to one side, as just described, the hair must be drawn into the frame, through the teeth 14 and it is desirable that all of the hair, so drawn in, should come from that portion of the hair not yet waved. In other words, when, on the ordinary devices of this nature, the comb is moved, a portion of the hair is drawn in from both sides of the waver, tending to disturb the wave just completed. In order that, when performing the waving operation where the hair is first crimped along one line and then crimped along an adjacent parallel line, the hair drawn in may be wholly from the uncrimped or unwaved side, means are provided to prevent clamping operation by the fork finger by that side at which it is not desired to draw in the hair. This arrangement calls for tilting the fork member and such tilting is possible by reason of the elongated slot 48 by which it is mounted on the stud 43. The means for effecting the tilting operation consists of a bar 50 pivotally mounted on a stud 51 which is shiftable into either end or into the leg of a T-shaped slot 49. If in either end of the slot 49, it is disposed in obstructing relation to one or the other of the fork fingers 45. If in the leg of the slot 49, it is out of obstructing position to either of the fork fingers. A bonnet nut 52 is connected with the stud 51 and serves to clamp that in any position in which it is desired to dispose it in the slot 49. A spring 53 surrounding the stud serves to hold the bar 50 in a position transversely of the device but to permit its rocking in either direction.

In the marceling operation, the crimping is started at the part in the hair and worked to either side and the bar 50 is positioned to obstruct either one of the fingers 45, depending on which side of the head the waving is being done. If, for example, the waving is being done on the left hand side of the head, the bar is positioned as shown in Figure 5, so that the left hand fork finger 45 is prevented reaching the bottom of its slot, while the right hand finger is not. While the normal position of the bar is transverse, it may be shifted out of such transverse position by means of the projection or lug 54 on the under edge of the lever 34, for when the lever is depressed to shift the comb 27, its lug 54 engages and deflects the bar 50 out of its obstructing position to the fork finger, so that the finger may then enter its slot. The first crimping or waving the hair is done adjacent the part, and if the waving be done on the left hand side of the head, with the bar positioned as shown in Figure 5, the first wave will be formed, after which the device will be moved laterally to the point where the next wave is to be formed and as the members are closed, the right hand finger 45 will enter the full depth of the slot and thus clamp the hair therein, but the other finger will not because of the obstructing position of the bar 50. Thus, when the comb is operated which will mean that the strands of hair will be drawn in, all of these strands will come in over that finger which is abutting the bar 50. After the lever reaches the position where the lug 54 engages the bar 50, the latter will be shifted out of position and the hitherto restrained finger 45 will enter fully in its slot and fully clamp the hair. The device functions in the same way when marceling the hair on the other side of the head but this is of course attended with the

shifting of the bar 50 to the opposite end of the leg of the slot 49.

The hereinbefore described construction admits of considerable modifications without departing from the invention; therefore, it is the wish not to be limited to the precise arrangements shown and described, which are as aforesaid by way of illustration merely. In other words, the scope of protection contemplated is to be taken solely from the appended claims, interpreted as broadly as is consistent with the prior art.

What is claimed is:

1. A hair waving device comprising an elongated hollow body having a transversely curved surface, heating means carried in the hollow of said body, elongated spaced legs, loose pivotal means movably mounting said legs on said body, and manipulable means terminally carried on the respective body and legs for moving the latter into adjacent relation with opposite sides of said surface to engage hair in waved condition on said surface, a comb structure slidably mounted on the curved surface of said body, a lever pivotally mounted on said body and adapted to move said comb structure longitudinally of the body, said body having a rectangular opening therein, a stop structure carried in said opening and adapted to be secured at either end of said opening, said stop structure being adapted to engage one of the legs when said legs are partially drawn into a position adjacent to said body and means for disengaging said stop structure from said leg after said slideable comb has been moved, thereby allowing the hair to be drawn in to the body from one side thereof only.

2. A hair waving device comprising a body comprising a cross-sectionally U-shaped member the free edges of whose flanges are formed with teeth, a heating element of cross-sectionally arcuate form and disposed in said U-shaped

member with the peak of the arch spaced from the web of the U-shaped member to provide between the two a conductor receiving channel and hair receiving channels between said heating element and the flanges of said U-shaped member, a fork pivotally mounted on the body and having spaced legs one of which is receivable in each of the hair receiving channels, a comb slidably mounted on the under face of the heating element and on the body and formed with teeth protruding beyond the legs of said fork when said legs are in the hair receiving channel, and manual means mounted on the body and operatively connected with the fork for imparting longitudinal movement to it relative to the body.

3. A hair waving device comprising a body comprising a cross-sectionally U-shaped member the free edges of whose flanges are formed with teeth, a heating element of cross-sectionally arcuate form and disposed in said U-shaped member with the peak of the arch spaced from the web of the U-shaped member to provide between the two a conductor receiving channel and hair receiving channels between said heating element and the flanges of said U-shaped member, a fork pivotally mounted on the body and having spaced legs one of which is receivable in each of the hair receiving channels, a comb slidably mounted on the under face of the heating element and on the body and formed with teeth protruding beyond the legs of said fork when said legs are in the hair receiving channel, and manual means mounted on the body and operatively connected with the fork for imparting longitudinal movement to it relative to the body, the teeth of the fork being relatively wide and of arcuate form, their width being slightly less than the distance between the legs of the fork.
